UNITED STATES PATENT OFFICE.

JACOB H. GENTER, OF NEWBURGH, NEW YORK.

SCREEN FOR MOVING PICTURES.

1,128,867.

Specification of Letters Patent. Patented Feb. 16, 1915.

Application filed June 12, 1912. Serial No. 703,148.

To all whom it may concern:

Be it known that I, JACOB H. GENTER, a citizen of the United States, and a resident of Newburgh, in the county of Orange and 5 State of New York, have made certain new and useful Improvements in Screens for Moving Pictures, of which the following is a specification.

My invention relates to improvements in 10 screens for receiving and projecting images such as those of stereopticons or moving picture machines, and it consists in the constructions herein described and claimed.

An object of my invention is to provide a 15 screen which is actually made up of a series of strips, but which appears to be a unitary structure without any seams.

A further object of my invention is to provide a screen which will not subject the 20 eye to strain, glare, or haze.

A further object of my invention is to provide a screen by means of which the projected images may be readily seen without the necessity of putting out the lights in the 25 house or theater in which the exhibition is being held.

Other objects and advantages will appear in the following specification, and the novel features of the invention will be particularly pointed out in the appended claims.

My invention is illustrated in the accompanying drawings in which—

Figure 1 is a section through a portion of the screen, Fig. 2 is a front view of a portion of the screen, Fig. 3 is an enlarged detail view of a portion of the screen showing its embossed surface, Fig. 4 is an enlarged section showing the embossed surface, and Fig. 5 is a modified form of the device.

In carrying out my invention I provide a suitable body portion consisting of flexible strips such as those shown at A and B in Fig. 1. These strips are preferably of some flexible fabric, such as canvas, or the 45 like, although they may be made of tough paper or other suitable material. In making the screen the edges of the strips A and B which abut each other are trued off so that when they meet on the common line a (see Fig. 2) the surfaces register. On the 50 back of the screen or curtain and overlapping the adjacent ends of the strips A and B is a layer of similar flexible material C. This may be cemented to the strips A and 55 B by means of cement D, as shown in Fig. 1, or it may be sewed directly to the strips

A and B by stitching E, as shown in Fig. 5. It will be understood that one or more of these joints may be made as the size of a screen warrants. After the strips A and B 60 have been joined together an exterior filling or coating F is applied to the screen. The composition of this coating forms the subject of a co-pending application, Serial Number 703,331, filed June 12, 1912. In 65 general it may be stated that it consists of an amalgam of any suitable metal, such as tin, silver, gold, aluminum, etc., which is held in suspension by means of a vehicle such as collodion. The coating or filling F 70 is applied by scraping the same over the front portion of the screen to which it will adhere. It will be noted that this coating or filling tends to cover up whatever may be seen of the small line which marks the edges 75 of the adjacent strips A and B, so that when the coating F dries, the result is that the seam is not visible, and the appearance of the screen is that of a unitary structure. This is, of course, of great importance in 80 screens of this type, as where there is a seam it detracts from the picture. After the coating has dried, which only takes a few minutes, the screen is passed through an embossing machine which makes an embossed surface similar to that shown in 85 Figs. 3 and 4. It will be understood, of course, that the ridges G, which are shown in Figs. 3 and 4, are, of course, greatly exaggerated. The appearance of the screen 90 to most of the audience is that of a perfectly flat surface, but the embossing of the screen has a tendency to diffuse the light which it reflects, and therefore there will not be the glare which results from the reflection of a 95 bright light upon a plain surface. A screen made in this manner can be manufactured from narrow strips of material, and is therefore cheaper to manufacture. The hiding of the seam gives the screen the appearance 100 of a single flat surface, and there is not the unsightly appearance of the seam which tends to detract from the picture. The embossing of the surface tends further to hide the seam, and, as stated before, it diffuses the light, eliminates the glare, and gives the picture a soft and finished effect which cannot be produced by a plain surface. For 105 small narrow theaters the embossing is not heavy, but for wide theaters in which the 110 picture is viewed from an angle I find that heavy embossing is best, since it eliminates

distortion from the angular view. Moreover a screen thus made at close view gives a depth of perspective which cannot be obtained on the ordinary screen, while the picture stands out clearly and does not grow dim or blurred when viewed from a short distance.

I claim:—

1. In a screen, a plurality of flexible strips, the edges of said strips being straight and the front and rear surfaces of the strips being arranged to register, a flexible reinforcing member secured to the back of the screen and arranged to overlap the edges of the abutting strips, a coating or filling on the front side of the screen for hiding the abutting edges of the strips, and auxiliary means for aiding in the concealment of the edges of the strips and for diffusing the light.
2. In a screen, a plurality of flexible strips, the edges of said strips being straight and the front and rear surfaces of the strips being arranged to register, a flexible reinforcing member secured to the back of the screen and arranged to overlap the edges of the abutting strips, and a coating or filling on the front side of the screen for hiding the abutting edges of the strips, the front face of the screen being embossed for diffusing the light and for the purpose of aiding in the concealment of the edges of the strips.

3. In a screen for moving pictures, a plurality of opaque flexible strips, the edges of said strips being straight and the front and rear surfaces of the strips being arranged to register, a flexible fabric reinforcing member secured to the back of adjacent strips and arranged to overlap the abutting edges, and a reflecting coating or filling on the front side of the screen for hiding the abutting edges of the strips, the front face of the screen being embossed for diffusing the light and for the purpose of concealment of the edges of the strips.

4. In a screen for moving pictures, a plurality of opaque flexible strips, the edges of said strips being straight and the front and rear surfaces on one strip being arranged to register with the front and rear surfaces respectively of the adjacent strips, a flexible fabric reinforcing member secured to the back of adjacent strips and arranged to overlap the abutting edges, and a reflecting coating or filling on the front side of the screen for hiding the abutting edges of the strips, the front face of the screen being embossed with a plurality of irregular shaped ridges for the purpose of diffusing the light and for aiding in the concealment of the edges of the strips.

JACOB H. GENTER.
